US00D939162S

(12) **United States Design Patent** (10) **Patent No.:** **US D939,162 S**
(45) **Date of Patent:** **** Dec. 21, 2021**

(54) **FABRIC STEAMER APPARATUS**

(71) Applicant: **Conair Corporation**, Stamford, CT (US)

(72) Inventor: **Kin Man Lai**, Wu Kai Sha (HK)

(73) Assignee: **Conair LLC**, Stamford, CT (US)

(**) Term: **15 Years**

(21) Appl. No.: **29/732,002**

(22) Filed: **Apr. 20, 2020**

(51) **LOC (13) Cl.** **15-05**

(52) **U.S. Cl.**

USPC **D32/17**

(57) **CLAIM**

The ornamental design for a fabric steamer apparatus, as shown and described.

DESCRIPTION

FIG. 1 is a front perspective view of a fabric steamer apparatus, according to the present invention;

FIG. 2 is a front elevational view of the fabric steamer apparatus of FIG. 1;

FIG. 3 is a rear elevational view of the fabric steamer apparatus of FIG. 1;

FIG. 4 is a right side elevational view of the fabric steamer apparatus of FIG. 1;

FIG. 5 is a left side elevational view of the fabric steamer apparatus of FIG. 1;

FIG. 6 is a top plan view of the fabric steamer apparatus of FIG. 1; and,

FIG. 7 is a bottom plan view of the fabric steamer apparatus of FIG. 1.

1 Claim, 6 Drawing Sheets
